UNITED STATES PATENT OFFICE

2,317,776

PHOTOELECTRIC CELL

Emil Körber, Nuremberg, Germany; vested in the
Alien Property CustodianApplication October 24, 1939, Serial No. 300,993
In Germany October 24, 1938

2 Claims. (Cl. 136—89)

This invention relates to photo-electric cells, and more particularly to new and useful methods of manufacturing blocking layer photo-electric cells.

It is a known expedient in the art when blocking layer photo-electric cells of the stack-type are concerned to place or form a layer of a semi-conductive material on a metallic base plate or electrode and to cover this layer with a light-permeable counterelectrode of high electric conductivity; a blocking layer being formed between the semi-conductor and the light-permeable counterelectrode either in response to a suitable treatment of the superficies of the semi-conductor, in a chemical reaction between the counterelectrode and the semi-conductor, or by an artificially applied film of insulation which stands in no genetic relation either to the semi-conduction layer or to the counterelectrode, the thickness of such film being in the order of only a few molecules.

The present invention has for an object to provide new methods of manufacturing photo-electric cells of the above-mentioned type, according to which the production of such cells may be considerably simplified and the properties of the product resulting therefrom be essentially improved.

The manner in carrying out my invention and further objects thereof will be fully understood from the following description taken in conjunction with the accompanying drawing; the Figs. 1 and 2 thereof in strongly exaggerated scale embodying the same photo-electric cell during different steps of the manufacturing process according to this invention.

In realizing the skill of this invention, a semi-conductive layer B overlaying a metallic base plate A constituting one of the electrodes of the photo-electric cells to be produced, is coated, preferably by vaporization, with a thin layer C of a suitable electrically non-conductive metallic compound, whereupon the superficies of the layer C is converted by reduction into the metal forming the constituent of the metallic compound as shown in Fig. 2, in which C'' denotes the substantially pure metallic layer or counterelectrode and C' indicates the remainder of the non-conductive compound which is unaffected by the reduction medium and which forms the blocking layer of the cell. This expedient involves the beneficial advantage that, in addition

to the formation of a highly conductive and uniformly distributed light-permeable counterelectrode, a blocking layer is simultaneously formed by the lower surface of the electrically non-conductive metallic compound which remains unaffected by the reduction medium.

In making the choice among the metallic compounds which may be considered suitable for application onto the semi-conductive layer overlaying the base plate electrode, care must be taken that such electrically non-conductive compound together with the semi-conductive layer does not form any undesired compound or compounds which may obstruct or upset the effect of the blocking layer.

The essential improvement secured according to the method of this invention over the heretofore known methods resides in the fact that the uniformity of the resulting blocking layer photo-electric cell and, hence, the adaptation with respect to different service conditions may be governed at will by correspondingly dimensioning the thickness of the non-conductive compound and by governing the rate of penetration of the reductive or disintegrating medium.

In applying the now disclosed method to blocking layer photo-electric cells in which selenium forms the semi-conductive layer, the most satisfactory results have been obtained by evaporizing a layer of cadmium oxide onto the selenium and subsequently by exposing the cadmium oxide layer to nascent hydrogen which by reduction converts the superficies of the cadmium oxide into metallic cadmium. This reduction preferably may be accomplished by glow discharge.

What is claimed is:

1. The method of manufacturing blocking layer photo-electric cells which comprises, applying by vaporization a thin layer of cadmium oxide on the light-sensitive semi-conducting layer of selenium overlaying a metallic base plate, and disintegrating the cadmium oxide under the influence of nascent hydrogen.

2. The method of manufacturing photo-electric cells having a blocking layer which comprises coating a conductive base plate with a light sensitive layer of selenium, applying on said selenium layer a thin layer of cadmium oxide and reducing the surface of said cadmium oxide layer by subjecting it to the action of nascent hydrogen.

EMIL KÖRBER.
